STOCKING

Albert Rudelt, Philadelphia, Pa., assignor of one-third to Minisac Mills, Inc., a corporation of Pennsylvania, and one-third to S. & R. Textile Co., Inc., a corporation of Pennsylvania, both of Philadelphia, Pa., and one-third to Robert Hosiery Mills, Trappe, Pa., a copartnership

Application May 31, 1950, Serial No. 10,285

Term of patent 14 years

(Cl. D47—7)

To all whom it may concern:

Be it known that I, Albert Rudelt, a citizen of the United States of America, residing at Philadelphia, in the county of Philadelphia and State of Pennsylvania, have invented a new, original, and ornamental Design for Stockings, of which the following is a specification, reference being had to the accompanying drawing, forming a part thereof.

In the drawing:

I claim:

The ornamental design for a stocking, as shown.

ALBERT RUDELT.
